(57) **CLAIM**

The ornamental design for a multifunction printer as shown and described.

DESCRIPTION

3.1 : Front

3.2 : Back

3.3 : Left

3.4 : Right

3.5 : Top

3.6 : Perspective

The design product is used as a multifunction printer having the functions of printing, copying, scanning, faxing, etc.; the bottom view of this design is omitted since the bottom surface of the product is not easily visible or not visible in use and does not contain ornamental features and forms no part of the claimed design.

The broken lines immediately adjacent to the claim and defining additional broken line regions depict the bounds of the claimed design, while all other broken lines are directed to environment. The broken lines form no part of the claimed design.
